AUTOMOBILE FENDER GUIDE

Harry Ferman, Newark, N. J.

Original application February 29, 1952, Ser. No. 18,729, now Patent No. D.170,632, dated October 20, 1953. Divided and this application September 1, 1953, Serial No. 26,896

Term of patent 14 years

(Cl. D14—6)

To all whom it may concern:

Be it known that I, Harry Ferman, a citizen of the United States of America, residing at Newark, New Jersey, have invented a new, original, and ornamental Design for Automobile Fender Guide, of which the following is a specification, reference being had to the accompanying drawing, forming part thereof.

Fig. 1 is a front view of an automobile fender guide, showing my new design.

Fig. 2 is a top view of Fig. 1.

Fig. 3 is a bottom view of Fig. 1.

This application is a division of application Serial Number D.18,729 filed February 29, 1952, which has matured to Design Patent D. 170,632 on October 20, 1953.

I claim:

The ornamental design for an automobile fender guide, as shown and described.
